UNITED STATES PATENT OFFICE.

WALLACE H. McCORMICK, OF STREATOR, ILLINOIS.

HOIST FOR DUMPING TRUCKS.

Application filed February 21, 1924, Serial No. 694,213.

To all whom it may concern:

Be it known that I, WALLACE H. McCORMICK, a citizen of the United States, and resident of Streator, county of La Salle, and

5 State of Illinois, have invented certain new and useful Improvements in Hoists for Dumping Trucks, of which the following is a specification, and which are illustrated in the accompanying drawings, forming a part 10 thereof.

This invention relates to hoisting devices, and more particularly to hoisting devices for dumping trucks and the like.

One of the objects of the invention is the 15 provision of an attachment for trucks that is provided with new and improved power multiplying body hoisting and lowering mechanism.

Another object of the invention is the provision of new and improved hoisting mechanism together with means for removably mounting the same on the chassis frame of a vehicle.

Other objects of the invention are the 25 provision of a new and improved hoisting device that is simple in construction, cheap to manufacture, readily assembled, efficient and powerful in operation, easily manipulated, and that is not likely to become broken 30 or get out of order.

Other and further objects and advantages of the invention will appear from the following description, taken in connection with the accompanying drawings, in which

35 Fig. 1 is a side elevation of a dumping truck, with parts broken away;

Fig. 2 is a section on line 2—2 of Fig. 1;

Fig. 3 is a section on line 3—3 of Fig. 1, with parts omitted;

40 Fig. 4 is a section on line 4—4 of Fig. 5;

Fig. 5 is a section on line 5—5 of Fig. 4;

Fig. 6 is a perspective view of the supporting member;

45 Fig. 7 is a perspective view of one of the attaching members to which the hoisting chain or cable is attached;

Fig. 8 is a perspective view of a latch for holding the gears in mesh;

50 Fig. 9 is a modified form of attaching means for the device;

Fig. 10 is a section on line 10—10 of Fig. 9; and

55 Figs. 11 and 12 show a still further modified form of attaching means.

On the drawing the reference character 10 designates a motor truck provided with

chassis frame 11, wheels 12 and cab 13, as is usual in such constructions. The body 14, provided with longitudinal sills or supporting members 15, is pivotally mounted at its rear end, as at 16, to the chassis frame 11. 60

The sills 15 may, if desired, be so arranged that they will engage and be supported directly by the side members of the chassis frame 11. 65

Since the details of the truck form no part of the present invention the same is not shown and will not be further described.

Suitable means are provided for elevating or hoisting the front or free end of the body 70 14. Preferably this means is so constructed that it constitutes a unitary structure that may be attached to or detached from the truck and is provided with means whereby the same may be adjustably connected to 75 any suitable dumping truck.

As shown, the hoisting attachment comprises a channel or U-shaped support 17 which is provided with slots 18 in its base portion at each end thereof, whereby the 80 same may be attached to the flanges 19 of the chassis frame 11 as by means of the bolts 20, see Figs. 3 and 6.

The support 17 may also be provided with a slot 21 which permits the escape of dirt 85 and other foreign matter from said support.

Mounted in the ends of the support 17 are the two part bearings 22 and 23 in which are adapted to be journaled the reduced ends of the drum or winding shaft 24. The 90 lower portions 25 and 26 of these bearings are adapted to fit the channel of the support 17 and are adapted to be secured thereto by bolts 27 which also secure the upper portions 28 and 29 of the bearings in proper 95 position.

The support is also provided with a suitable mast 30 which comprises the standards 31 and the upper cross members 32. The brace members 33 may, if desired, be also 100 employed.

In order to relieve the mast from unnecessary strain, the same is preferably pivotally mounted. As shown, the lower ends of the standards 31 are provided with the hinge members 34. The hinge members 34 are 105 preferably provided with ledges 35 on which the standards 31 are adapted to be supported. The standards as shown are in the form of angle bars, but it is understood that they may be of any other suitable form.

The hinge members 34 are connected to

the standards 31 by rivets or any other suitable fastening means. The hinge members 34 are adapted to be pivotally mounted on the reduced ends of the drum or winding shaft 24, as clearly shown in Fig. 4. In order to take the end thrusts the lower portions 25 and 26 of the journals 22 and 23 are provided with extensions 36 having concave upper surfaces that form bearings for the lower ends of the members 34.

The members 34 are provided with shoulders 37 which are adapted to engage corresponding shoulders on the extensions 36 for limiting the forward pivotal movement of the standards 31. The shoulders 37 may also engage the forward flange of the support 17, as shown in Fig. 12. Pulleys 38 are journaled on the cross members 32 and are adapted to have trained over the same, flexible members such as the chains 39, one end of each of which is connected to the winding shaft or drum 24 as at 40. The other ends of the chains are secured to the attaching member 41 carried by the front ends of the sills 15 of the body 14. The attaching members 41 are provided with offsets 42 whereby the chains will hang in vertical planes and be prevented from coming in contact with the standards 31 during the raising and lowering of the vehicle body.

Suitable means are provided for rotating the drum 24 for winding up the chains 39. Preferably power multiplying gears are employed for this purpose. As shown, one end of the drum 24 has rigidly mounted thereon the gear 43. The gear 43 is operated by the pinion 44 which is rigidly connected to the gear 45. The pinion 44 and gear 45 are supported in any suitable manner. As shown, the bearing 26 is provided with the flange 46 to which the plate 47 is adapted to be secured, as by means of the bolts 48 and 49, see Figs. 4 and 5. These bolts are provided with spacing sleeves and the pinion 44 and gear 45 are journaled on the sleeve on the bolt 48.

The gear 45 is adapted to be rotated by means of the pinion 51 which is rigidly mounted on the stub shaft 52, one end of which is journaled in the drum 24 and the other end of which extends through a bracket extension 53 of the plate 47. The outer end of the shaft is provided with a ratchet 54 which is adapted to be engaged by the pawl 55 integral with or rigidly secured to the crank 56. A plate 57 connected to the crank 56 is provided with a slot 58 through which the shaft 52 extends. This slot permits the crank 56 to be moved outward to withdraw the pawl 55 from the ratchet 54. The spring 59 on the shaft 52 between the collar 61 and plate 57 creates sufficient friction to hold the crank 56 from moving outward and disengaging the pawl 55 from the ratchet 54. A catch 62 is provided on the

cab 13 for engaging the crank 56 for holding the same in inoperative position against the pressure of the spring 59.

In order to facilitate the lowering of the body and avoid accidents during the lowering operation, it is desirable that means be provided whereby the stub shaft will not rotate during this operation. As shown, the shaft 52 is slideable longitudinally of its axis. The pinion 51 is held in mesh with the gear 45 by means of the pivoted latch 63 which is provided with a depending portion 64 adapted to engage the boss 65 on said pinion. The pinion 51 may be disengaged from the gear 45 by elevating the latch 63 and moving the stub shaft outwardly. The extension of the shaft 52 is of such length that it will not become disengaged from the drum 24 when the boss 65 is drawn outwardly against the bracket 53.

Suitable means are provided for controlling the descent of the truck body. As shown, a brake is employed for this purpose. The brake may be in the form of a band 66 secured at one end to one of the bolts 49 and having its other end secured to a lever 67. The lever 67 is provided with a hinged extension or handle 68 for operating the brake. The extension is adapted to swing down out of the path of the crank 56.

A pawl 69 is adapted to engage the teeth of the pinion 45 for holding the body at any desired elevation. The pawl is held in operative position by a suitable spring 71. The pawl is so constructed that it will ride over the teeth of the gear 45 during the elevation of the body 14. The pawl is released by the member 72 which is connected to the lever 67 in such a manner that when the pawl is released the brake is applied.

Suitable means are provided for protecting the gearing from dust and other foreign matter. As shown, the upper section 29 of the bearing 23 is provided with a flange 70 to which is secured the curved shield 75, which extends over said gearing. The shield 75 may be provided with a flange 76 at its outer end.

The forward ends of the sills 15 are provided with concave notches 78 which are adapted to afford clearance for the drum 24 whereby the front part of the body when in lowered position is adjacent to the cab 13.

In Figs. 9 and 10 is shown a modified form of attaching the support 17 to the chassis frame 11. In this construction clamping plates 73 are employed for this purpose. The supports are clamped against the frame 11 by means of suitable bolts 74, those on the outside of the frame 11 being also adapted to hold the journal 23 in position.

In the form of the device shown in Figs. 11 and 12 the support 17 is secured to the chassis frame by means of additional at-

taching members 77 which are secured to the support by bolts which adjustably engage the slots 18 in said support. The free ends of the attaching members 77 are adapted to conform to the channel of the side members of the frame and are secured thereto by any suitable means. In order not to weaken the chassis frame the fastening means preferably extends through openings 39 in the neutral axis of the longitudinal frame members.

In the operation of the device, when the body is in lowered position and it is desired to dump the same, the crank 56 is released from the catch 62 and the same is slid inward until the pawl 55 engages the ratchet 54, after which the crank may be turned to rotate the drum 24 for winding up the chains 39 to elevate the front end of the body. If the load be heavy the crank 56 may be oscillated from the position most convenient for the operator. The pawl 69 will hold the drum in any position to which it may be turned. When it is desired to lower the body, the latch 63 is turned upward and the crank 56, together with the stub-shaft 52 are moved outward disengaging the pinion 51 from the gear 45. The handle or extension 68 is moved upward to operate the lever 67 for elevating the pawl 69 and applying the brake band 66 to the periphery of the gear 45 for controlling the descent of the body 14 which is accomplished by the force of gravity.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. An attachment for motor vehicles comprising a support having an upwardly extending flange, means for securing said support to a vehicle, a drum mounted on said support, a mast pivotally mounted on said drum and having a shoulder for engaging said flange for limiting the pivotal move-

ment of said mast in one direction, a pulley at the upper end of said mast, a flexible member trained about said pulley and having one end secured to said drum, and means for rotating said drum.

55

2. A unitary attachment for dumping trucks comprising a U-shaped support, bearings secured in said support, a winding drum journaled in said bearings, extensions on said bearings, a mast comprising arms pivoted to said drum, and shoulders on said arms for engaging said extensions for limiting the pivotal movement of said arms.

60

3. A hoisting mechanism for dumping vehicles comprising body elevating mechanism, including a winding drum, means for operating said mechanism comprising a series of power multiplying gears connected to said drum, a stub shaft having one end slidably journaled in said drum, a pinion on said shaft for driving said gears, means for releasably holding said pinion in mesh with one of said gears, and a crank for rotating said stub shaft.

65

4. A hoist for dumping trucks comprising a body elevating mechanism including a winding drum, a train of gears for rotating said drum, a stub shaft having its inner end slidably mounted in one end of said drum, a pinion keyed to said shaft and adapted to drive said train of gears, a latch for holding said pinion in operative position, a pawl for engaging said train of gears to prevent backward rotation of the same, a brake for said train of gears, and a sectional lever for simultaneously operating said pawl and brake.

75

5. A hoist for vehicles comprising body elevating mechanism including a drum, a train of gears for operating said drum, means including a crank for operating said gears, means whereby said crank may be moved laterally to inoperative position, a pawl and brake for engaging certain of said gears, and an extension lever for simultaneously operating said pawl and brake for permitting backward rotation of said drum when said crank is moved to inoperative position and for controlling said rotation.
